UNITED STATES PATENT OFFICE.

GEORGE W. CUMMINGS, OF COHOES, NEW YORK.

KNITTING-MACHINE.

SPECIFICATION forming part of Letters Patent No. 595,698, dated December 21, 1897.

Application filed February 25, 1896. Serial No. 580,712. (No model.)

To all whom it may concern:

Be it known that I, GEORGE W. CUMMINGS, a citizen of the United States, residing at Cohoes, in the county of Albany and State of New York, have invented new and useful Improvements in Knitting-Machines, of which the following is a specification.

My invention relates to improvements in knitting-machines and is designed to be applied to the same for producing knitted plush fabrics; and it consists of the devices and combinations of devices and elements hereinafter described, and set forth in the claims.

The objects of my invention are to arrange a landing-bur for operation with the fabric while in formation and with the backing-thread of the same after a sinking bur or wheel has operated with a tying-in thread, and also to provide, with a landing-bur, certain combinations of devices by means of which the said landing-bur may be nicely adjusted and be properly guarded and prevented from injuriously affecting the fabric. Other advantageous operations will be fully disclosed by the specification. I attain these objects by means illustrated in the accompanying drawings, forming a part of this specification, in which—

Figure 1 is a plan view of a portion of a machine embodying my invention with the "push-down" and its bracket removed. Fig. 2 is a side elevation of my landing-bur and the sinking-bur stand and adjuncts thereto. Fig. 3 is an elevation in the transverse and viewed from the inner side of the machine; and Fig. 4 is a side elevation of the push-down, guard, and elastic guard-shield employed with my landing-bur.

The same letters of reference refer to similar parts throughout the several views.

In the drawings, A is the cylinder, which may be of any preferred diameter and form of construction, supported from any suitable table and revolved by proper mechanism and preferably by shaft A', supported in bearings and driven by any preferred mechanism.

a are the usual needles, secured to shanks a', which are tightly clamped in place to cylinder A by clamping-pieces A² and screws a², as generally practiced by the trade.

B is the sinker-bur-stand bracket, carrying the sinker-bur stand B' and adjustable hori-

zontal bracket B² and their respective adjuncts and co-operating devices usually employed in knitting-machines, which adjuncts and devices I will briefly refer to in the drawings, as they are generally old and well-known devices which are employed by me in combination with the devices which are my invention. Of these old devices, C is the plush-bur, suitably supported on shaft c, carried by radial arm C', which has secured to its outer end the backing-thread guide c'. This arm C' is adjustable within the split clamping-sleeve C², carried by the vertical bracket C³, secured in an adjustable manner to the horizontal bracket B², adjustable on the stand-bracket B.

D is the clearing-bur, mounted at an angle on a suitable spindle carried by the radial arm D', having secured to its outer end the tying-in-thread guide d. This arm D' is adjustable in the split clamping-sleeve D², carried by the vertical bracket D³, secured adjustably with the horizontal bracket B².

E is the sinker-bur, arranged at the outer side of the circular line of needles, mounted on a suitable spindle e, set at an angle to the needles and in a line at an inclination opposite to that of the axis of the spindle of the clearing-bur D, and is carried by the inner end of the radial spring-actuated arm E', contained in the sleeve F, secured to the vertical bracket-standard B, which may be vertically adjusted in either direction, as may be required. This spring-actuated arm E' may be nicely adjusted by means of the finger-nuts usually employed for that purpose, so as to control the pressure of the sinker-bur E against the needles, and thereby properly carry the threads said bur operates with down to such a degree as may be desired.

G is a second radial sleeve supported by a suitable standard G' and capable of being vertically adjusted on the same. Within said sleeve works the spring-actuated arm G², similar to spring-actuated arm E' in sleeve F and carrying by its inner bracket end the pintle g, arranged on an angle in the same line of direction as the pintle e, and on this pintle g is mounted the sinker-bur H, which operates with the face-thread running from a suitable face-thread guide to said bur.

I is a spring-actuated presser secured to the

head end of the spring-actuated arm I', working in sleeve I², secured within the split clamping-sleeve I³, supported by any suitable bracket, as i, secured to the stem end G. A 5 pin i', secured to the spring-actuated arm I' and working in the short guiding-slot i², holds the presser I to its work at the needles.

These several devices, as above mentioned, are old and their operations are so well known 10 to the trade that description of their operations with the needles, their adjuncts, and threads are therefore unnecessary at this time.

I have introduced into the knitting mechanisms above described of the knitting-machine a new element for operation with the backing thread or threads, which in the fabric produced furnishes the loops or shags constituting in the finished fabric the plush elements of the same, so that the shag of the plush side of the fabric is made to have new and distinguishing characteristics and features not before found in other knitted plush fabrics. These new elements which give to 25 the fabric the distinguishing features and characteristics referred to may be produced by different mechanisms operating with the backing thread or threads, yet I at present give preference to the employment of the new 30 devices shown in the drawings as being the simplest and most advantageous for use.

In these new devices K is the landing-bur for operation with the backing-thread T, first carried to the needles by the plush-bur C. 35 This landing-bur is arranged within the circle of the inner sides of the needles aa of the cylinder and has its axis of revolution at an angle to the needles and inclining downwardly and in the direction of revolution of the cylinder, as 40 indicated by arrows in Fig. 1. This landing-bur is mounted on the lower end of spindle K' and freely revolves on the same, with the burs or blades of this landing bur or wheel K so acting with the needles from their inner sides as to carry the backing-thread up 45 preparatory to the fabric receiving the face-thread and after the tying-in thread T' has been interwoven with it. This bur K is readily adjustable in any direction and may 50 be so made by any suitable means, yet I preferably employ for that purpose the attaching-sleeve L, applied to the outer end portion of arm M, through which sleeve the upper end 55 of spindle K' transversely passes and is adjustably secured by set-screw k, Figs. 1, 2, and 3. A split clamping-sleeve N, provided with clamping-screw m, receives the said arm M and when loosened allows said arm to be moved horizontally in either direction. The 60 cross-head N', Fig. 3, is preferably integral with the split clamping-sleeve N and is provided with slot-form holes for receiving the holding-screws n, screwing into the bracket or standard B, as indicated by dotted lines in 65 Fig. 2. By means of these several devices, which are only adjuncts to this landing-bur, a nice adjustment of the latter in relation to

the needles for best operations may be readily effected.

P is a presser having bearing on the barbs 70 of the needles for pressing them inwardly at the time the backing-thread is being carried upwardly by the landing bur or wheel K, preparatory to running in the face-thread T², which is run from its bobbin (not shown) to 75 and through the thread-guide p and thence to a suitable tension device (not shown) and thence to the sinker bur or wheel II, before described. This presser is fixed on the inner or head end of the arm P', which latter freely 80 works in the adjustable sleeve P², shown to be clamped in the split sleeve P³ by means of clamping-screw p', and is guided by the guide-pin p², fixed in said arm and working in the guide-slot p³, provided in the said adjustable sleeve P². Spring R, between the shoulder of the head end of the presser-arm P' and the adjustable sleeve P², renders the presser elastic, and by means of the adjusting devices described the elastic pressure of 85 this presser on the barbs of the needles may be nicely adjusted. Although the drawings, Figs. 1 and 2, show the face-thread guide r for receiving the face-thread T to be supported from the rear end of the presser-arm 90 P', yet it may be supported by any other device or by an adjunct to the sleeve G or other piece.

The manner in which working parts of the knitting-machine embodying my invention 100 operate is as follows: The backing-thread T, which in the finished plush fabric comprises the loops or shags of the plush, may be of wool, cotton, or other vegetable or animal fiber or any suitable mixtures in desired proportions 105 of the same, as may be preferred for the class of articles to be produced. When the cylinder is revolved, this thread T runs from the bobbin (not shown) to the thread-guide c' and thence to the tension-piece, guiding the 110 thread to the plush-bur C and the needles in the usual manner. This backing-thread T is then carried by the needles to the clearing-bur D and passed down to the shanks of said needles. The tying-in thread T' is then run 115 from its bobbin (not shown) to and through the thread-guide d and thence to the usual tension-piece guide d', Fig. 3, at the sinker-bur E, which latter carries this tying-in thread under the barbs of the needles. All these 120 operations, being old, are so well known that a particular description is unnecessary. The new elements which I have provided for operation for producing an improved knitted plush fabric are now brought into action for 125 operating with the backing-thread T preparatory to working in the face-thread T². The revolutions of the cylinder being continued, the barbs of the needles are carried to the presser P and by it are pressed inwardly at 130 the same time the landing bur or wheel K operates to carry up the backing-thread T from the inner side of the circular series of needles preparatory to the face-thread T² being run

from the bobbins (not shown) into the needles and worked in with the tying-in thread T' by the operation of the sinker-bur H , which carries the face-thread to the needles at the same time the tying-in thread is being carried under the barbs of the needles and before the loops or shags produced from the backing-thread T are raised up and landed on the points of the barbs of the needles, ready to be cast off after the face-thread is worked in. Sinker-bur H now carries the face-thread under the barbs of the needles and lands it at the side of the tying-in thread. Then presser I closes the barbs of the needles, when the usual landing-bur (not shown, being well known) inside the circle of the needles lands the fabric preparatory for the operation of the cast-off bur (not shown, being well known) for casting off the finished fabric in which the three above-named threads are embodied.

The landing bur or wheel K being arranged for operation with the backing-thread from the inner circumferential line of the series of needles a , and the partly-formed fabric Q , produced by the backing-thread worked in with the tying-in thread, being wholly within inner circumferential line of the needles, I provide a suitable device for carrying the lower margin of the partly-finished fabric, while yet on the needles, to a suitable distance below the same. I also provide a suitable bur-receiving device for preventing the blades of the bur or wheel touching any portion of the fabric Q or any guarding device which may be interposed between the fabric Q and the bur K , and, further, I provide an elastic guard which interposes between the cup receiving the bur K and the fabric, so as to prevent the said cup from entering into any hole which may by accident be formed in the fabric, as by dropping stitches, which sometimes occur.

I at present prefer to employ as a device for carrying the lower margin portion q of the fabric Q below the plane of the base-line of the needles the push-down piece S , (shown by full lines in Fig. 4,) which piece is made of thin metal and curved horizontally to correspond with the curve of the line of the shanks a' of the needles at a point a little below the base ends of the latter. With the lower margin of this push-down piece is provided the downwardly-projected convex-form runner s , which is preferably wholly below the plane of the lower side of the landing-bur K and serves to press the fabric Q , directly below said bur, down to a short distance below the same, as shown in Fig. 2. This piece S has provided in it the opening t , which allows the spindle K' , bur K , and its cup U to be adjusted horizontally in either direction on arm M . S' is a suitable arm adjustably secured to post S^2 , preferably connected to standard B and set with its face side inclining and having in it the vertical slot s' , (indicated by full and dotted lines,) in which slot is received a tongue portion s^2 of said arm, (indicated by

dotted lines in Fig. 2,) while a clamping-screw s^3 , passing through a clamping-washer s^4 and screwing into a screw-threaded perforation in said tongue portion, operates to force the shoulder s^5 of arm S' and the washer s^4 toward each other for clamping the metal at the sides of said slot and securely hold the said arm at the place it may be adjusted on said post. By this adjustability of said arm S' the push-down piece S may be raised or lowered, as may be required, for nice adjustment in relation to the landing-bur.

U is a cup for receiving the landing-bur, and it may be made as a piece separate from the spindle K' and be secured to the lower end thereof by any preferred means, yet I prefer to make this bur-receiving cup integral with said spindle K' by forming it with the lower end of said spindle and recessing this cup from its upper side, as indicated by dotted lines in Fig. 4, so that said bur may be received therein when slipped on the spindle K' from its upper end before being secured to the arm M . The side of this cup U opposite the needles a is removed for allowing the blades of the bur K to project to said needles, as shown in Figs. 1 and 2.

V is the cup-guard, preferably formed of a strip of elastic thin metal and arranged horizontally in front of the bur-cup U and supported in place from the body of the push-down piece S , preferably by one end thereof being secured to said piece S by rivets or screws, while the opposite end thereof is free and the body thereof is convex on its side adjoining the fabric Q , so as to allow this cup-guard to receive the pressure of the said fabric as it is carried by the revolution of the cylinder without liability of it catching in the same. Although this push-down piece, bur-receiving cup, and guard shown are each of a form I at present prefer, yet I do not confine myself to the construction shown of said parts and the means by which they may be supported in place or adjusted, as they may be variously modified by exercise of ordinary judgment and skill.

Having described my invention, what I claim, and desire to secure by Letters Patent, is—

1. In a knitting-machine, the combination with the needles of a revolving cylinder, of an adjustable spindle supported and arranged within the needles and at an angle or incline in direction toward the direction of the motion of said revolving cylinder, of a cup, and a landing bur or wheel contained in said cup and mounted on the lower end of said spindle and adapted to operate with the backing-thread received by said needles, substantially as and for the purposes set forth.

2. In a knitting-machine, the combination with a landing bur or wheel arranged with its axis of revolution at an angle in relation to the needles of a revolving cylinder, and in place between the cast-off portion of the finished fabric and the inner sides of the nee-

dles, of a landing-bur cup inclosing both the lower end portion and the inner peripheral portion of said landing bur or wheel and supported from the spindle on which said bur 5 revolves, for intervention between the latter and the finished fabric, substantially as and for the purposes set forth.

3. In a knitting-machine the combination with a landing bur or wheel arranged with its 10 axis of revolution at an angle in relation to the needles of a revolving cylinder and in position between the inner sides of the needles and the finished fabric, of a guard arranged in position between said landing bur 15 or wheel and said fabric substantially as and for the purposes set forth.

4. In a knitting-machine the combination with a landing bur or wheel and the landing-bur cup open at its outer side for projection 20 of the burs or blades of said landing-bur among the inner sides of the needles, of a cup-guard calculated to prevent the said cup engaging with any perforations which may

accidentally be produced in the fabric, substantially as and for the purposes set forth. 25

5. In a knitting-machine the combination with a landing bur or wheel arranged between the inner side line of the circular row of needles of a revolving cylinder and the later-finished portion of the fabric and a cup receiving 30 said landing-bur, of a push-down device having a rigid support from a stationary adjunct of the machine and provided with an opening for receiving the major portion of the landing-bur and its cup, with the lower 35 side edge of said push-down device calculated to have bearing on the lower margin portion of the fabric at the needles and progressively crowd down the finished fabric below the lower side of the landing bur or wheel, between the latter and the needles, substantially as and for the purposes set forth. 40

GEORGE W. CUMMINGS.
